(57) CLAIM

The ornamental design for a lighter, as shown and described.

DESCRIPTION

FIG. 1 is a perspective view of a lighter showing my new design with a tether attached;

FIG. 2 is a front elevational view thereof;

FIG. 3 is a rear elevational view thereof;

FIG. 4 is a top plan view thereof;

FIG. 5 is a bottom plan view thereof.

FIG. 6 is a left side elevational view thereof;

FIG. 7 is a right side elevational view thereof; and,

FIG. 8 is a perspective view thereof showing the top of the

lighter in an open position and with the tether attached.
The portions shown in broken lines are included for illustrative purposes only and form no part of the claimed design.
